TELLING MACHINE COMPANY, OF BOSTON, MASSACHUSETTS, A CORPORATION
OF MAINE.

MACHINE FOR FELLING WAISTBANDS OF TROUSERS.

1,087,268.

Specification of Letters Patent. Patented Feb. 17, 1914.

Application filed December 17, 1908. Serial No. 468,049.

To all whom it may concern:

Be it known that I, WILLIAM E. BAILEY, a citizen of the United States, and a resident of Beverly, in the county of Essex and 5 State of Massachusetts, have invented an Improvement in Machines for Felling Waistbands of Trousers, of which the following description, in connection with the accompanying drawing, is a specification, 10 like letters on the drawing representing like parts.

This invention relates to a machine for blindstitching wherein the stitches enter and emerge on the same surface of the goods 15 and the stitch-forming mechanism is located entirely at one side of the goods.

The invention in many of its features is particularly adapted for use in the felling of the upper edges of trousers where the 20 lining is felled to the main fabric on the wrong side after buttons and belt straps, either or both, have been attached to the right side of the fabric at or near the upper edge.

25 The invention involves improvements in the feeding mechanism, in the bender mechanism for projecting the fabric into the path of the needles in the work-support and particularly in a movable section thereof where- 30 by irregularities in the goods are controlled in their passage past the stitching point, in the means for guiding the edge of the fabric, in the construction of the presser-foot, and in other features which will more fully 35 appear from the description and drawings, and will be particularly pointed out in the claims.

The drawings illustrate the invention as embodied in its preferred form, and in a 40 machine suitable for felling the lining to the outer material of the upper edge of a pair of trousers whether either buttons or belt straps or both occur at intervals.

Figure 1 is a front elevation of the ma- 45 chine. Fig. 2 is a side elevation of the forward end of the feeding instrumentality. Fig. 3 is a front elevation of the lower end of the feeding instrumentality. Fig. 4 is a front elevation, partially in cross-section, of 50 the lower portion of the presser-foot. Fig. 5 is a top plan view of the work-support and the lower portion of the presser-foot. Fig. 6 is a top plan view of the lower por-

tion of the feeding instrumentality. Fig. 7 is a side elevation of the parts shown in 55 Fig. 6. Fig. 8 is a side elevation of the presser-foot detached. Fig. 9 is a cross-section through the work-support taken on the line $x-x$, Fig. 5.

Certain features of the machine it is unnecessary to describe in detail because specifically considered they form no part of the present invention, and are similar in construction to the well-known Arbetter type of machine illustrated for example in patents to Arbetter No. 830,699, granted September 11, 1906, No. 937,273 granted Oct. 19, 1909.

In its general arrangement the machine comprises a bed-plate A and an overhanging arm A², only the forward portions of which are herein illustrated. The bed-plate A has mounted and vertically movable therein a carriage E³, carrying the work-support E. This carriage E³ is retained in 75 vertical guideways by means of the face-plate E⁴, attached to the bed-plate or lower portion of the machine by screws E⁷. The work-support with its carriage is normally elevated by means of the spring E⁸ and is 80 depressed when required, as for placing the work in position by means of a manually-operated lever (not shown). The overhanging arm A² supports and carries the entire 85 stitch-forming mechanism, and the presser-foot, as in the case of the Arbetter type of machine, and in the embodiment of the invention illustrated the overhanging arm carries the entire feeding mechanism, so that the stitch-forming mechanism, the 90 feeding mechanism, and the presser-foot are in this form located upon one and the same side of the work, or as herein illustrated above the work-support.

The stitch-forming mechanism itself is 95 fully illustrated in the before-mentioned patents and comprises, as therein described, the curved needle a², mounted in the needle-carrying arm b¹, carried in turn by the needle-carrying rock-shaft B⁷, journaled in 100 the long transverse bearing B⁸, carried by the vertical rock-shaft B¹⁰, to which the rocking motion is imparted at the proper times, as set forth in said patents, to cause the needle to move at one time parallel with, 105 and at another time diagonal to the feed.

This movement of the needle enables one stitch to be taken into the base fabric close up to and parallel with the edge of the overlying fabric, and another stitch to be taken 5 diagonally into the overlying fabric at its edge. The stitch-forming mechanism further comprises a suitable complementary mechanism, herein shown as a revolving hook a , with an inclosed bobbin case a^3 containing the usual bobbin. The revolving hook a is mounted in the holder A^8 depending from the overhanging arm, and is arranged to revolve in a plane slightly oblique to the vertical and transversely of the paths 10 of reciprocation of the needle.

The main driving shaft of the machine is indicated at A^3 , and from it the stitch-forming mechanism is driven in suitable manner, as set forth in the above-mentioned 20 patents. The connections for rocking the needle-carrier and rock-shaft B^7 are illustrated and comprise a disk a^8 on the end of the driving shaft A^3 , and a rod B^2 connecting a stud on the disk to a crank arm on 25 the shaft B^7 .

The presser-foot D is adjustably connected by the set-screw D^2 to the presser-foot holder D^3 , which in turn is rigidly connected with the overhanging arm of the machine. 30

Owing to the peculiar character of the work for which the machine illustrated is particularly designed, the construction of the work-support, presser-foot, feeding 35 mechanism, and edge-gage is of particular importance. The invention in its broader aspects is not restricted to the particular construction of these parts illustrated and now to be described, but these constructions 40 of themselves involve certain additional features of novelty by reason of which they are adapted to coöperate in handling the particular class of work, viz., the felling of the upper edge of trousers. In work of

45 this character the commercial requirements are such that the lining must be felled to the inner folded, upper edge of the trousers after the buttons, and the belt straps (when used) have been fastened on the opposite 50 side of the goods. The work thus presents buttons protruding from the right side of the goods, and when they are used straps protruding not only from the right side of the goods but also projecting beyond the 55 upper edge. At intervals also seams frequently occur, running transversely to the edge of the trousers. The occurrence of all these irregularities renders it an exceedingly difficult proposition to fell on the lining 60 on the opposite side of the folded edge of the trousers by machine and at the same time secure neat and regular work. This work is accomplished by the machine herein illustrated.

65 The work-support E is provided with a

separate section E^{12} , pivoted at E^{13} in a bracket E^{14} secured by screws E^{15} to the top-plate of the work-support E . The pivotal axis is arranged transversely of the line of feed in a vertical plane extending 70 through the position where the stitch is taken in the goods, or in other words about in line with the bender which acts to project the work into the path of the needle. The effect of thus pivoting a section of the 75 work-support is to enable all irregularities, such as the extra thicknesses caused by the transverse seams or by the belt straps, to pass between the fixed presser-foot and the work-support without causing the separation 80 of the presser-foot and work-support when the points of normal thickness of the work are passing between at the stitching point. When such an unusual thickness enters beneath the presser-foot the movable section rocks downwardly at its forward 85 end, thus maintaining the presser-foot and work-support in coöperation at the stitching point, and as the point of extra thickness passes on it is properly handled itself 90 at the stitching point, and as it passes the stitching point causes the movable section of the work-support to tilt in the opposite direction and allow it to pass out from between the presser-foot and work-support 95 readily.

The movable section E^{12} of the work-support is grooved longitudinally, as indicated at E^{16} , to provide a passageway for the buttons projecting from the right face of the 100 fabric, and the entrance to this passageway is made flaring, as indicated at E^{17} , to prevent the buttons from catching as they come along. The movable section E^{12} is thus a trough-shaped device and is closed at its 105 top, except for the longitudinal opening to allow for the passage of the neck or fastening portion of the buttons, by plates E^{18} fastened in place by screws.

The mechanism for operating the bender 110 is similar to that illustrated in the above-mentioned patents. The bender bar G^2 is mounted to slide vertically in bearings G^3 formed on the plate E^6 , and is given its upward movement from a crank arm G^4 carried by the shaft G^5 . The buttons on this 115 class of work usually project beyond the line along which the lining is felled to the inner folded edge of the goods, and hence a bender such as shown in the above-mentioned 120 patents is useless. The present invention provides a bender having a shank G^6 mounted in a socket G^7 carried by the bracket E^{14} . The shank of the bender is bent or offset at its upper end so that while the shank passes up outside of the path of the button the effective end G of the bender is in the proper position beneath the path of the needle and over the button. The bender is normally held in a depressed or inactive position by 125 130

- the coiled spring G^8 , surrounding the socket G^7 and engaging a pin G^9 projecting from the shank G^6 . The bender bar G^2 is provided with an offset G^{10} projecting beneath the shank G^6 so that at the proper time upon the movement of the crank arm G^4 the bender bar will be elevated into contact with the shank G^6 and cause the effective end G of the bender to project the material into the path of the needle.
- The presser-foot is shaped to coöperate with the work-support and maintain an effective control of the goods at the stitching point. The usual opening or needle throat is provided for the operation of the needle and bender. The paths of the needle in making the straight and diagonal stitches are indicated in the dotted lines H in Fig. 5. The heel portion of the presser-foot is concaved, as indicated at D^4 , to present a thin edge near the throat and allow for the passage of the needle thereover, and this edge is extended to form the fingers D^5 , D^6 , the finger D^5 being upwardly curved at its point. The presser-foot is also cut away to form an elongated opening D^7 to the right of the bender to provide for the positive feeding of the goods by the feeding dog at this point. The presser-foot is cut away at its toe to present an edge D^8 which acts as a guide for the folded edge of the lining. The edge of the presser-foot is also grooved or cut away, as indicated at D^9 , and provided with an upwardly curved projection D^{10} adjacent the throat, so that as the folded edge of the lining passes along it will be led up through the groove D^9 and lifted by the projection D^{10} , the upwardly curved end of the finger D^5 allowing it to be thus lifted, so that the needle in its diagonal stroke may readily pass beneath the folded edge of the lining. The presser-foot is also slotted at D^{12} to allow for the passage of the edge-gage to be described.
- In order to guide the edge of the main portion of the goods, or that portion to which the lining, buttons and straps are secured, an edge-gage K is provided. This edge-gage is secured to a vertically movable bar K^2 mounted in bearings K^3 on the plate E^6 . A bell-crank lever K^4 , fulcrumed at K^5 on the frame of the machine, is slidingly connected at one end to the gage K and provided with a handle K^6 at its opposite end, so that the gage may be raised and lowered by the operator when desired. The mounting of the gage upon the frame of the machine enables its raised position to be maintained irrespective of the up and down movement of the work-support, so that when the gage is raised to project into the presser-foot it will maintain that position notwithstanding the passage of any irregularities over the work-support or any movement of the work-support. This gage is ar-

ranged to guide the edge of the goods and can be thrown down whenever a strap or other projection comes along.

The feeding mechanism operates entirely upon the upper surface of the goods and is supported from the overhanging arm of the machine. It comprises a feed-dog P which is given in any suitable manner its proper feeding movements from the driving shaft, A^8 . In the embodiment of the invention illustrated the feeding dog P is secured by set-screw P^2 to a lever P^3 fulcrumed at P^4 in the overhanging arm. The lever and overhanging arm are slotted so that the fulcrum pin P^4 may be moved up and down to adjust the throw of the feed dog. The upper end of the lever embraces the cams P^6 and P^7 carried by the driving shaft, one of the cams acting to give the longitudinal and the other the up and down movement to the feed dog, and by means of these cams any desired movement can be given to the feed dog.

The feed dog is shaped to coöperate with the presser-foot and work-support in properly feeding the goods past the stitching point, and to this end it is provided with a section P^8 moving above the work-support at the left of the presser-foot, and also with a section P^9 operating over the slot through which the button neck passes, and preferably extending well throughout the length of this slot, and also with a short section P^{10} operating at the right of the bender and provided with a lateral projection P^{11} which operates over the path of the bender. By thus constructing the presser-foot the goods are firmly gripped and held and fed along so that there can be no shifting of the goods from the proper position.

Having described my invention, what I claim as new and desire to secure by Letters Patent, is:

1. A blindstitch sewing machine comprising stitch-forming mechanism and a stationary presser-foot located above the work, feeding mechanism, a yieldingly-mounted work-support located below the work, a section of the work-support being pivoted transversely to the line of feed near the stitching point, the said section extending beneath the presser foot and on both sides of the stitching point, whereby the said section will rock on its pivot to allow of the passage of irregularities in the work and maintain the control of the goods between the presser-foot and the work-support at the stitching point.

2. A blindstitch sewing machine comprising stitch-forming mechanism and a stationary presser-foot located above the work, a yieldingly-mounted work-support located below the work, a section of the work-support being pivoted transversely to the line of feed near the stitching point, the said section extending beneath the presser foot and on both sides of the stitching point, whereby the said section will rock on its pivot to allow of the passage of irregularities in the work and maintain the control of the goods between the presser-foot and the work-support at the stitching point.

- both sides of the stitching point, feeding mechanism located above the work-support, and means for operating it to feed the work over said pivoted section.
5. 3. A blindstitch sewing machine comprising stitch-forming mechanism and a stationary presser-foot located above the work, a yieldingly-mounted work-support located below the work, said work-support presenting a button passageway with a narrow opening extending in the line of feed, feeding mechanism located above the work-support, and means for operating it to feed the work over said work-support. 70
10. 4. A blindstitch sewing machine comprising stitch-forming mechanism and a stationary presser-foot located above the work, a yieldingly-mounted work-support located below the work, a section of the said work-support beneath the presser-foot presenting a button passageway with a narrow opening extending in the line of feed and being pivoted transversely to the line of feed near the stitching point, feeding mechanism located above the work-support, and means for operating it to feed the work over said pivoted section. 75
15. 5. A blindstitch sewing machine comprising stitch-forming mechanism and a stationary presser-foot located above the work, a yieldingly-mounted work-support located below the work, said work-support presenting a button passageway with a narrow opening extending in the line of feed, feeding mechanism including a feed dog located above the work-support, said feed dog presenting feeding projections above and at each side of said opening, and means for operating said feeding mechanism to cause the feed dog to feed the work over said work-support. 80
20. 6. A blindstitch sewing machine comprising stitch-forming mechanism and a stationary presser-foot located above the work, a yieldingly-mounted work-support located below the work, a section of the said work-support beneath the presser-foot presenting a button passageway with a narrow opening extending in the line of feed near the stitching point, a bender mounted on said yielding work-support to reciprocate through said pivoted section and offset at its point to place the path of movement of said point above said passageway, and means located and operative independently of said yielding work-support for operating said bender to cause it to project the work into the path of the needle at the required times. 85
25. 7. A blindstitch sewing machine comprising stitch-forming mechanism and a stationary presser-foot located above the work, a yieldingly-mounted work-support located below the work, a section of the said work-support beneath the presser-foot presenting a button passageway with a narrow opening extending in the line of feed and being pivoted transversely to the line of feed near the stitching point, feeding mechanism including a feed dog located above the work-support, said feed dog presenting feeding projections above and at each side of said opening, and means for operating said feeding mechanism to cause the feed dog to feed the work over said pivoted section. 90
30. 8. A blindstitch sewing machine comprising stitch-forming mechanism and a stationary presser-foot located above the work, a yieldingly-mounted work-support located below the work, said work-support presenting a button passageway with a narrow opening extending in the line of feed near the stitching point, a bender mounted on said yielding work-support to reciprocate through said pivoted section and offset at its point to place the path of movement of said point above said passageway, and means located and operative independently of said yielding work-support for operating said bender to cause it to project the work into the path of the needle at the required times. 95
35. 9. A blindstitch sewing machine comprising stitch-forming mechanism and a stationary presser-foot located above the work, a yieldingly-mounted work-support located below the work, a section of the said work-support beneath the presser-foot presenting a button passageway with a narrow opening extending in the line of feed and being pivoted transversely to the line of feed near the stitching point, feeding mechanism including a feed dog located above the work-support, said feed dog presenting feeding projections above and at each side of said opening, and means for operating said feeding mechanism to cause the feed dog to feed the work over said pivoted section. 100
40. 10. A blindstitch sewing machine comprising stitch-forming mechanism and a stationary presser-foot located above the work, a yieldingly-mounted work-support located below the work, said work-support presenting a button passageway provided with a narrow opening extending in the line of feed, a bender carried by and mounted to reciprocate in said yielding work-support and offset at its point to place the path of movement of said point above said passageway, means carried by and mounted in a fixed portion of the said machine independently of said yielding work-support for operating said bender to cause it to project the work into the path of the needle at the required times. 105
45. 11. A blindstitch sewing machine comprising stitch forming mechanism and a stationary presser-foot located above the work, a yieldingly-mounted work-support located below the work and provided with a bender opening, a bender, means for reciprocating the bender through said opening, feeding mechanism including a feed dog located above the work-support, said feed dog presenting feeding projections to act upon the work at each side of the bender opening. 110
50. 12. A blindstitch sewing machine comprising stitch forming mechanism and a stationary presser-foot located above the work, a yieldingly-mounted work-support located below the work and provided with a bender opening, a bender, means for reciprocating the bender through said opening, feeding mechanism including a feed dog located above the work-support, said feed dog presenting feeding projections to act upon the work at each side of the bender opening. 115
55. 13. A blindstitch sewing machine comprising stitch forming mechanism and a stationary presser-foot located above the work, a yieldingly-mounted work-support located below the work and provided with a bender opening, a bender, means for reciprocating the bender through said opening, feeding mechanism including a feed dog located above the work-support, said feed dog presenting feeding projections to act upon the work at each side of the bender opening. 120
60. 14. A blindstitch sewing machine comprising stitch forming mechanism and a stationary presser-foot located above the work, a yieldingly-mounted work-support located below the work, said work-support presenting a button passageway with a narrow opening extending in the line of feed, a bender mounted to reciprocate in said work-support and offset at its point to place the path of movement of said point above said passageway, means carried by and mounted in a fixed portion of the said machine independently of said yielding work-support for operating said bender to cause it to project the work into the path of the needle at the required times. 125
65. 15. A blindstitch sewing machine comprising stitch forming mechanism and a stationary presser-foot located above the work, a yieldingly-mounted work-support located below the work, said work-support presenting a button passageway with a narrow opening extending in the line of feed, a bender mounted to reciprocate in said work-support and offset at its point to place the path of movement of said point above said passageway, means carried by and mounted in a fixed portion of the said machine independently of said yielding work-support for operating said bender to cause it to project the work into the path of the needle at the required times. 130

12. A blindstitch sewing machine comprising stitch forming mechanism and a stationary presser-foot located above the work, a yieldingly-mounted work-support located below the work and provided with a bender opening, a bender, means for reciprocating the bender through said opening, feeding mechanism including a feed dog located above the work-support, said feed dog presenting feeding projections to act upon the work at each side of the bender opening and having a narrow transverse projection to move over the bender opening. 5
13. A blindstitch sewing machine comprising stitch-forming mechanism and a stationary presser-foot located above the work, a yieldingly-mounted work-support located below the work, a movable edge gage mounted in a fixed portion of the machine and projecting through an opening in the yielding work-support and engaging the presser-foot, and means for elevating and depressing the edge gage whereby when the edge gage is elevated the work-support may be moved independently thereof. 10
14. A blindstitch sewing machine comprising stitch-forming mechanism and a stationary presser-foot located above the work, a yieldingly-mounted work-support located below the work, a section of the work-support beneath the presser-foot being pivoted transversely to the line of feed near the stitching point, a movable edge gage mounted in a fixed portion of the machine and projecting through the pivoted section of the work-support into engagement with the presser-foot, and means for elevating and depressing said edge gage independently of the movement of the work-support and the movement of its pivoted section. 15
15. A blindstitch sewing machine comprising stitch forming mechanism located above the work, a work support located below the work, said work support presenting a button passageway provided with a narrow opening extending in the line of feed, feeding mechanism located above the work support and means for operating it to feed the work over said work support. 20
16. A blind stitch sewing machine comprising stitch forming mechanism located above the work, a work support located below the work, said work support presenting a button passageway with a narrow opening extending in the line of feed, feeding mechanism including a feed dog located above the work support, said feed dog presenting feeding projections above and at each side of said opening, and means for operating said feeding mechanism to cause the feed dog to move over said work support. 25
17. A blind stitch sewing machine comprising stitch forming mechanism located above the work, a work support located below the work, said work support presenting a button passageway with a narrow opening extending in the line of feed, a bender mounted to reciprocate in said work support, said bender having an offset to prevent interference with a button passing through said passageway during the reciprocation of the bender, and means for operating said bender to cause it to project the work into the path of the needle at the required times. 30
18. A blind stitch sewing machine comprising stitch forming mechanism located above the work, a work support located below the work, a section of the said work support beneath the presser foot presenting a button passageway with a narrow opening extending in the line of feed, said section being pivoted transversely to the line of feed near the stitching point. 35

In testimony whereof, I have signed my name to this specification, in the presence of two subscribing witnesses.

WILLIAM E. BAILEY.
